ELECTRONIC SPARK GENERATOR

Allan W. Lindberg, Webster Groves, and James C. Rombach, Rock Hill, Mo., assignors to Missouri Automatic Control Corporation, St. Louis, Mo., a corporation of Missouri

Application October 5, 1951, Serial No. 249,852

2 Claims. (Cl. 315—206)

1

This invention relates generally to spark ignition devices and more particularly to an electronic spark ignitor capable of producing continued arcing of suitable strength and size so as to be, for example, a reliable ignition means for pressure spray-type oil burners.

The usual spark ignition devices used in connection with oil burners employ a massive and costly transformer having a high ratio of secondary to primary winding in order to develop the sufficiently high voltage necessary to produce a spark adequate for the purpose. In the present invention, it is the primary object to provide a generally new and improved spark ignition device suitable for oil burner ignition use, in which a substantial saving in cost, and use of materials in critically short supply, is achieved and in which a substantial reduction in weight is accomplished.

A further object of the invention is to provide a spark ignition device in which sufficiently high potential to produce a satisfactory arc is obtained by supplying energy to a relatively small transformer intermittently and cutting off the supply abruptly at the termination of each interval without the use of mechanical motion or make and break contacts.

A further object is to provide a spark generator as above capable of producing continuous arcing at high frequency and of such strength as to be suitable for oil burner ignition.

More specifically, it is an object to provide an oscillator spark generator circuit having a transformer winding in the plate circuit of a grid-controlled electron discharge tube and a feedback from transformer to grid, in which the circuit oscillates free from the flywheel effect or circuit resonance so as to permit the flow of current in the transformer winding to be cut off sharply at maximum tube output upon reversal of the feedback signal at tube saturation, thereby to provide an unusually high induced voltage for bridging a spark gap.

These and other objects and advantages will appear from the following complete description when read in connection with the accompanying drawing.

The single figure of the drawing is a diagrammatic illustration of a form of the present invention.

Referring to the drawing, numeral 10 generally

5 indicates an electron tube which is preferably a high vacuum pentode having a plate 11, a suppressor grid 12, a screen grid 13, a control grid 14, a cathode 15, and a cathode heater 16. A transformer is generally indicated at 17, having a primary winding 18 series connected in the plate circuit of tube 10. Connected across the primary winding 18 is a spark-gap circuit including a transformer secondary winding 19 and a pair of 10 spaced electrodes (spark-gap) 20 and 21. The suppressor grid 12 is internally connected to the cathode 15 and the screen grid 13 is connected to the circuit power supply ahead of the transformer 17. The cathode heater 16 may be supplied energy in any suitable manner as by a small transformer (not shown).

15 A low impedance feedback to tube 10 is provided by a winding 22 which is in inductive relation with transformer primary winding 18 and 20 is connected to the control grid 14. A resistor 23 is included in the connection between winding 22 and the control grid so as to limit the current flow through the control grid cathode circuit to a value which may be safely carried by the grid.

25 The power supply to the above circuit is shown as being a 110 volt, 60 cycle, A. C. commercial source supplied through leads 24 and 25, which is half-wave rectified by the provision of a selenium rectifier 26 and filtered by the provision of 30 an inductance 27 and capacitors 28 and 29. While this power supply provides a satisfactory arc for the purpose, it will be understood that the slight additional cost of full-wave rectification will produce a stronger arc at 20—21. In order to provide 35 an unusually high induced voltage in the transformer primary winding 19, any lumped capacitance has been avoided, the circuit generally being designed with a view to reducing capacitance to a minimum and the windings 18, 19, and 40 22 have been designed with relation to the discharge tube characteristics so that oscillation of the circuit due to interaction between output and feedback occurs at a frequency considerably below the resonant frequency of the circuit. With 45 this arrangement, the cut-off of current flow through the transformer, which occurs at tube saturation, will be sharp and not rounded off in the usual sine wave form, which would otherwise occur if the circuit included appreciable capacitance and were oscillating at resonant frequency.

The use of a single high vacuum pentode tube provides the high output necessary to produce a strong arc, and while a triode may, of course, be substituted for a pentode, it is doubtful that the output of a single triode would be sufficient at the plate voltage of the usual 110 volt supply to provide the strength of arc necessary for dependable ignition of oil burners.

In operation

In starting, the control grid potential is zero, there being no bias. When the cathode 15 becomes sufficiently heated, the tube 19 begins to discharge and a flow of current through the plate circuit begins, also starting from zero. As current starts to flow through the plate circuit, this change causes a voltage to be induced in the feedback winding 22 resulting in a positive charge on the control grid. This positive feedback to the control grid further increases the tube discharge and consequently the plate current. The interaction is cumulative and, there being no limiting or bias of the control grid the plate current rises to the point of maximum tube discharge, the plate voltage being adequate. When maximum tube discharge is reached, the rate of increase of current flow through winding 18 stops and, consequently, the feedback to the control grid drops to zero.

The drop in positive grid potential results in a decrease in tube discharge and plate current. As the plate current decreases, the polarity of the induced feedback is reversed and the control grid rapidly becomes strongly negative, driving the tube beyond cut-off. This reversal from a strong positive to a strong negative grid occurs, of course, very rapidly at the point where tube output ceases to increase because of the cumulative interaction of decreasing plate current and decreasing signal. As a result of this abrupt collapse of plate current, a high potential is self-induced in the primary winding 18 and a high potential is induced in the secondary winding 19 by mutual induction. The inductances 18 and 19 being series connected across the spark gap electrodes 20-21, the sum of these potentials draws an arc across the electrodes suitable for the purpose. When the energy in coils 18 and 19 is dissipated by the arc, the circuit relaxes, the control grid potential returns to zero, and the circuit is ready to repeat the cycle.

The waveform of the current supplied to the transformer is therefore not sinusoidal but rather of general saw-tooth form. By delivering energy to the transformer in this manner, energy is delivered in increasing value and stored throughout for the greater part of the cycle and the precipitous cut-off, which ends the cycle, results in an extremely high induced voltage for bridging the spark gap. While some distributed capacitance in the inductances of the circuit is unavoidable, the circuit is, nevertheless, designed so that the frequency at which the circuit cycles due to the interaction between output and feedback never approaches the resonant frequency of the circuit. The grid circuit having low impedance, the grid returns to zero quickly.

By way of example, the following values were used in the illustrated circuit with 110 volt, half-wave, rectified input current and resulted in a satisfactory arc for ignition of oil burners occur-

ring at a frequency of approximately 1800 cycles per second.

Electron tube 10=a commercial 6AU5 pentode.

TRANSFORMER DATA

Primary Winding 18, 667 turns	Secondary Winding 19, 714 turns	Feedback Winding 22, 200 turns
Inductance=0.3 henry Resistance=35 ohms	Ind.=0.3 henry Res.=220 ohms	Ind.=0.029 henry Res.=2 ohms

Mutual inductances

Winding 18 to 19=0.27 henry

Winding 18 to 22=0.09 henry

Winding 19 to 22=0.07 henry

The resistor 23=1000 ohms.

It is to be understood that the characteristics and frequency of occurrence of the resulting ignition spark can be varied by the use of other types of electron discharge tubes and by other values of the inductances and resistor than those set forth hereinabove by way of example. The foregoing is, therefore, intended to be illustrative and not limiting, the scope of the invention being set forth in the appended claims.

I claim:

1. A spark generator circuit comprising a transformer having a primary and secondary winding, a pair of leads for connection with a source of power, a grid-controlled electron discharge tube series connected with said primary winding across said leads, a pair of spaced electrodes having such circuit connections with said transformer that potential induced in said transformer secondary winding is impressed on the air gap between them, and a feedback winding in inductive relationship with said primary winding and having one side thereof connected to the tube cathode, the capacitance of the circuit being sufficiently low and the relationship of the constants of the external elements of the circuit to the constants of the tube being such that said circuit oscillates freely due to interaction between output and feedback at a frequency substantially below the resonant frequency of the circuit.

2. A spark generator circuit comprising a transformer having a primary winding and a secondary winding, a pair of spaced electrodes series connected with said secondary winding across said primary winding, a pair of leads for connection with a source of power, a grid-controlled electron discharge tube series connected with said primary winding across said leads, and a feedback winding in inductive relationship with said primary winding and having one side thereof connected to the tube control grid and its other side connected to the tube cathode, said circuit being so designed as to reduce the capacitance therein to a point wherein the cut-off of current flow through said transformer due to interaction between feed back and tube output is abrupt and not appreciably affected by carry-over due to capacitive reactance.
